(57) **CLAIM**

The ornamental design for a rocket target game accessory, as shown and described.

DESCRIPTION

The present application is related to commonly assigned U.S. Design patent application Ser. No. 29/635,364 filed 30 Jan. 2018.

FIG. 1 is a front upper perspective view of the rocket target game accessory.

FIG. 2 is a top front perspective view of the rocket target game accessory.

FIG. 3 is a back view of the rocket target game accessory.

FIG. 4 is a front view of the rocket target game accessory.

FIG. 5 is a right side view of the rocket target game accessory.

FIG. 6 is a left side view of the rocket target game accessory.

FIG. 7 is a top view of the rocket target game accessory; and,

FIG. 8 is a bottom view of the rocket target game accessory. The broken lines in the drawings show portions of the interior surfaces of the rocket target game accessory design and form no part of the claimed design.
